UNITED STATES PATENT OFFICE.

ANDREW EDWARD LESTER, OF NEW YORK, N. Y.

DESIGN FOR A PUZZLE BOX OR CASE.

SPECIFICATION forming part of Design No. 25,840, dated July 28, 1896.

Application filed May 26, 1896. Serial No. 593,195. Term of patent 31 years.

To all whom it may concern:

Be it known that I, ANDREW EDWARD LESTER, a citizen of the United States, residing at New York, in the county of New York and State of New York, have invented and produced a new and original Design for Puzzle Boxes or Cases, of which the following is a specification, reference being had to the accompanying drawings, forming a part thereof.

10 In the drawings forming part of this specification, Figure 1 represents a plan view of my improved puzzle box or casing; Fig. 2, a section thereof on the line 2 2, these two views being deemed necessary to fully illustrate my design.

15 The leading feature of my design consists in an oblong box or casing A, provided with a bottom a and a transparent cover B, the bottom of the box or casing being provided 20 with curved or segmental flanges D and D², which extend from the corner thereof on one side to the opposite corner on the same side, and with similar curved or segmental flanges d and d², which connect the corners on the 25 opposite side, the flanges D² and d² being separated from the flanges D and d by a narrow space which is similar in form to said flanges, as shown at d³, and the flanges D² and d² being shorter than the flanges D and d, so that 30 narrow spaces are formed between the ends thereof and the ends of the box or casing, and the ends of the flanges D and d connect with the sides of the box or casing, and said flanges are each provided with transverse passages 35 or openings, as shown at d², and on the outer and inner sides thereof are formed curved or segmental spaces d⁴, and at each side of the box or casing and outside of the curved or segmental flanges D and d are formed semi- 40 elliptical spaces which are provided with irregular-formed blocks E, F, G, H, K, L, M, N, O, and P, which are bounded on their inner sides by the curved or segmental chambers or

passages d⁶, and which are separated by transverse and longitudinal passages m and n, respectively, and outside of the blocks E, F, G, H, and K the spaces between the passages m are divided or broken by vertical transverse plates or flanges a and longitudinal plates or flanges a², this feature of the arrangement or 45 design being the same on both sides of the bottom of the box or casing, and at the ends of the box or casing in the triangular spaces formed by the curved or segmental flanges D² and d² the bottom A is also provided with 50 irregular blocks g, which are separated by transverse and longitudinal passages g² and g³, respectively, and said blocks g are also separated from the ends of the box or casing.

55 It is evident that slight changes may be 60 made in the formation of the various blocks and in the passages which separate the same, and also in the various plates or flanges, without departing from the spirit of my invention or sacrificing its advantages, and it will also 65 be observed that the general appearance of the blocks at the end of the box or casing is that of a triangle, with the base directed outwardly, while the arrangement on the sides is similar and symmetrical in form, thus giving 70 a perfectly symmetrical appearance to the entire arrangement.

Having fully described my invention, I claim as new and desire to secure by Letters Patent—

75 The design for a puzzle box or case, as herein shown and described.

In testimony that I claim the foregoing as my invention I have signed my name, in presence of the subscribing witnesses, this 31st 80 day of March, 1896.

ANDREW EDWARD LESTER.
